UNITED STATES PATENT OFFICE.

CARL SCHEVITZ, OF JACKSONVILLE, FLORIDA.

EXPANSIBLE SHOE-LAST.

1,379,478.

Specification of Letters Patent. Patented May 24, 1921.

Application filed July 30, 1920. Serial No. 400,018.

To all whom it may concern:

Be it known that I, CARL SCHEVITZ, a citizen of the United States, residing at Jacksonville, in the county of Duval and 5 State of Florida, have invented new and useful Improvements in Expansible Shoe-Lasts, of which the following is a specification.

This invention relates to shoe stretching 10 means, the present invention being an improvement over that forming the subject matter of a patent granted to me on December 23, 1919, Serial No. 1,326,100. One of the objects of the present invention is to 15 provide a casing for inclosing the working parts and to shape the heel frame so that it will conform to the shape of the heel part of the shoe and the handle part of the heel frame will form a part of the inclosing casing 20 when the device is not in use.

Another object of the invention is to so form the central portion of the device that it will conform to the arch and shank of the shoe when the device is placed in the shoe.

25 Another object of the invention is to provide means whereby the instep stretching member may have a greater degree of movement than in the former device and to positively connect said member with the frame 30 of the device.

In describing my invention in detail, reference will be had to the accompanying drawings wherein like characters denote like or corresponding parts throughout the several views, and in which:—

Figure 1 is an elevation of the improved device.

Fig. 2 is a longitudinal sectional view.

Fig. 3 is a plan view with parts in section.

Fig. 4 is a view of one of the cam frames.

Fig. 5 is a view of one of the sliding frames.

Fig. 6 is a view of the heel frame.

45 Fig. 7 is a view of the key for operating the various parts of the device.

Fig. 8 is a view of the instep stretching member.

Fig. 9 is a view of the side stretching 50 member.

Fig. 10 is a view of the toe member.

In these views 1 indicates the main frame which is formed with the inwardly extending offset portions 1', intermediate the ends 55 of its side bars for forming the contracted portions for fitting in the shank of the shoe.

The side bars of the frame are provided with the slots 2. At the rear of the main frame is secured the lower end of the upright 3. Within the main frame is located 60 a pair of longitudinally extending strips 4, said strips being spaced apart and their front ends having upwardly extending portions 5 which are slotted as at 6. These strips form a guideway for the longitudinally movable bar 7 which passes through an opening in the front cross piece of the main frame. The front end of said bar is provided with a spring pressed pin 8 and this end is adapted to receive the toe stretching member 9. The rear end of this bar is provided with a screw threaded bore which receives the screw threaded part of shaft 11. This shaft is connected with the upright shaft 12 by the gears 13. The shaft 12 is 70 carried by lugs 14 formed on the upright 3. The upper end of the shaft 12 is square so as to receive the squared socket of the key 15.

Associated with the main frame is the 80 heel frame 16 which is of substantially U-shape with the under edges of the legs of the U provided with a plurality of notches 17 and the upper edges at the ends of the legs provided with the projections 18. 85 These notches and projections are adapted to engage the projections 19 on the upright 3 to permit the adjustment of said heel frame. The heel frame is also provided with the handle 20.

A pair of sliding frames 21 are located in the spaces between the sides of the frame and the strips 4. These side frames are of yoke-shape with their limbs brought close together to fit in the contracted part of the main frame and they are each provided with a small laterally extending lug 22 at the extremity of one leg and an upwardly extending part 23 at the extremity of the other leg. Each leg is also provided with a pair 100 of elongated slots 24 which are adapted to register with the slots 2 in the main frame and with similar slots in the strips 4. The lugs 22 are also adapted to engage with the slots 2 in the main frame.

A pair of cam frames 25 are located in the frames 21 and both sets of frames are slidingly held in the main frame by the pins 26, a pair of which is carried by each of the cam frames, having their ends engaging the slots 24 in the frames 21 and the slots in the main frame and strips 4.

As shown in Fig. 4 the cam frames are of channel shape in cross section with one end closed and this closed end has an inclined corner 27, which forms a cam. These 5 cam frames are of the same general shape as the frames 21. The closed end of each cam frame is adapted to coöperate with the closed end of the frame 21 for adjusting the side stretching member 28.

10 The upwardly projecting part 23 of each of the frames 21 has pivoted thereto a rack bar 29, the teeth of which are adapted to engage a cross piece 30, which forms part of a channel bracket 31 secured to the 15 upright 3.

The rack bars are adapted to be held with their teeth engaging the cross piece by means of a rod 32 carrying a pin 33, which engages the upper edges of said rack bars, and 20 said rod is provided with a guide 34 at its lower end which has sliding engagement with the bracket 31. The rod 32 is normally held with its pin in engagement with the rack bars by a spring 35. The upper end of the 25 spring bears against a collar 36 loosely mounted on the rod and having its upper end engaging the bent over end 37 of the upright 3. The rod 32 passes through a key-hole-shaped opening in said bent end and 30 the rod is provided with a flat portion for engaging the small part of this opening so as to hold the rod in its upper position, against the tension of the spring and with the pin 33 out of engagement with the rack 35 bars to permit said bars to be moved longitudinally so as to adjust the frames 21.

A pair of curved arms 37 is connected with the rear part of the main frame by the 40 links 38 and the front ends of these arms 25 are pivotally connected to the cam frames by pins 39 passing through the reduced portions of said cam frames. The upper ends of the arms are pivotally connected to the socket members 41 and these socket members receive the ends of the screw threaded 45 shafts 42 which pass through the screw threaded collars 43. Said collars are held against rotation in the part 3' of the upright 3. The upper ends of the shafts 42 are 50 squared to receive the key 15.

An arm 44 is pivotally mounted to the bracket 45 which extends forwardly from the upright 3 and the front end of the said arm carries a roller 46 which is adapted to 55 engage the underface of the instep support 47. This arm is rocked about its pivotal point by means of the shaft 47' engaging a screw threaded socket carried by the bracket 45 and having its upper end passing through the part 3' and provided with a squared portion to receive the key 15. This shaft is 60 provided with a collar 48 for engaging the arm 44 to move the roller on said arm upwardly against the instep support to stretch the instep of the shoe. This support is pro-

vided with a pin 47" for engaging the slots 6 in the projections 5.

The above arrangement of parts is substantially similar to that described in the before mentioned patent with the exception 70 of the contracted central portion of the main frame and the sliding and cam frames. These contracted portions make the device fit the shank part of the shoe when placed therein. 75

I also provide a casing which is formed of two parts 50, each part being screwed to the rear face of the upright 3. This casing surrounds the upper part of the device and extends under the upper end of the instep member 47. The part 20 of the heel member 16 is of curved shape in cross section and will form the rear part of the casing when the device is in closed condition. 80

It will thus be seen that the interior parts 85 of the device will be covered up by the casing, the instep member 7 and the heel member 16. This member 16 is also formed to conform to the shape of the rear part of the shoe as will be seen from the drawings. 90

I also provide a bottom plate 51 for the device which is secured to the main frame 1 and this bottom plate is provided with a central arch part 52, the side bars of the main frame being cutaway at their lower 95 edges to receive this arch. This will make the device conform to the shape of the inner sole of the shoe.

I also form the toe member 9 with a curved recess 53 on each side of its stem 54 100 which is socketed to receive the end of the member 7. The instep member 47 is provided with a slot 55 at its front end and a pair of rounded extensions 56 on each side of the slot which will pass into the recesses 105 53 when the instep member is tilted upwardly. In this action the slot 55 receives the stem 54. This arrangement of parts will permit a greater degree of movement of the member 47 than in the former construction. 110

I also form the key 15 with a handle 15' of the shape shown in Fig. 7 and with a roughened extension 15" which projects above the handle. This will permit the key 115 to be rapidly rotated.

The operation of the device is as follows:—

The last is placed within the shoe and the heel frame adjusted to make the last fit the 120 shoe. The key is then placed on the shaft 12 and the same rotated to force the toe stretching means 9 into the toe. The key is then placed on shaft 47' to move the arm 44 to adjust the instep support to stretch the 125 instep. Then the key is placed on one of the shafts 42, according to which side the side stretching member 28 is located. By raising the rod 32 the rack bars are unlocked and by rotating the shaft by the key both the 130

cam frame and the side frame can be adjusted longitudinally to place the side stretching member 28 in its proper position. The frame 21 is locked by lowering the rod 32 so that upon further rotation of the shaft the cam frame will move within the frame 21 and thus press the shank 28' of the side stretching member 28 between the ends of the two frames and the pressure of 5 the cam 27 against the inclined face of the shank will cause said member 28 to move laterally away from the side of the main frame.

It will thus be seen that the whole adjustment may be carried out from the exterior 15 of the shoe so that it is not necessary to place the hands within the shoe.

When the locking rod 32 is in raised position the guide 34 will be raised so as to hold 20 the rack bars above the cross piece 30 and thus permit free movement of the frames 21.

The casing and the instep member will give the device the appearance of an ordinary last while at the same time protects the 25 working parts from dust and dirt and the formation of the casing, the heel plate and the bottom plate, as shown in Figs. 1 and 3 will make the device conform to the shape 30 of the interior of the shoe.

It is thought from the foregoing description that the advantages and novel features 35 of my invention will be readily apparent.

I desire it to be understood that I may make changes in the construction and in the 40 combination and arrangement of the several parts, provided that such changes fall within the scope of the appended claims.

What I claim is:—

1. An expandible shoe last comprising a 45 main frame having a contracted central portion, an upright member secured thereto at the rear thereof, slidable members in said frame, operating shafts for said members journaled in the upright member, a casing secured to the upright member and surrounding the shafts and provided with curved lower portions for conforming to the shape of the shoe and shoe expansion members connected with the slidable members.

50 2. A shoe last of the class described comprising a frame having a contracted central portion and an arched bottom, a bottom plate carried by the frame also having an arched part, slidable members in the frame, shoe expansion members carried by said 55 slidable members, an upright secured to the frame, shafts journaled therein for

actuating the slidable members, a casing secured to said upright and inclosing the shafts and having its lower part curved to 60 fit in the contracted portion of the frame, said casing being extended over the main frame and shaped to fit the shoe and an instep member connected with the front part of the frame and having its other end resting on the extended part of the casing. 65

3. A shoe last of the class described comprising a frame having a contracted central portion and an arched bottom, a bottom plate carried by the frame also having an 70 arched part, slidable members in the frame, shoe expansion members carried by said slidable members, an upright secured to the frame, shafts journaled therein for actuating the slidable members, a casing secured to said upright and inclosing the shafts and having its lower part curved to 75 fit in the contracted portion of the frame, said casing being extended over the main frame and shaped to fit the shoe, an instep 80 member connected with the front part of the frame and having its other end resting on the extended part of the casing, and a heel plate including a handle part of 85 curved shape in cross section and formed to conform to the rear part of the shoe.

4. A shoe last of the class described comprising a main frame, a slidable member therein, a toe stretching member connected with said slidable member, said toe member 90 being recessed, an instep stretching member pivotally connected at one end to the frame and having an extension adapted to engage the recess in the toe member when the said instep stretching member is tilted, means for 95 tilting said member and means for moving the slidable member.

5. A shoe last comprising a main frame having a contracted side portion for fitting in the shank of the shoe, a pair of slidable 100 frames located in the main frame, a cam frame located in each slidable frame, said slidable and cam frames having contracted portions working in the contracted portion of the main frame, a side stretching member 105 having a shank adapted to be engaged by the cam frame and means for moving the slidable frame and the cam frame to adjust the position of the side stretching member and to move the cam frame in the slidable 110 frame to force the side stretching member laterally.

In testimony whereof I affix my signature.
CARL SCHEVITZ.
